(57) **CLAIM**

The ornamental design for an electrical receptacle, as shown and described.

DESCRIPTION

FIG. 1 is a perspective view of the electrical receptacle showing my new design;

FIG. 2 is a top plan view of the electrical receptacle of FIG. 1; FIG. 3 is a bottom plan view of the electrical receptacle of FIG. 1;

FIG. 4 is a front elevation of the electrical receptacle of FIG. 1;

FIG. 5 is a rear elevation of the electrical receptacle of FIG. 1; FIG. 6 is a right side elevation of the electrical receptacle of FIG. 1; and,

FIG. 7 is a left side elevation of the electrical receptacle of FIG. 1.

The broken lines are included for the purpose of illustrating portions of the electrical receptacle that form no part of the claimed design.

1 Claim, 4 Drawing Sheets
